DENTAL UNIT

Raymond L. Roof, Paducah, Ky.

Application November 5, 1946, Serial No. 707,813

10 Claims. (Cl. 32—22)

1

This invention relates to dental equipment, and more particularly to a dental operating unit adapted to house and support instrumentalities generally and frequently employed by a dentist in the practice of his profession.

It is an important object of this invention to provide an improved unitary dental apparatus having parts so arranged as to contain and support the various instruments commonly used in the performance of dental operations.

Another important object of the invention is to provide a dental operating unit that is adapted to be readily moved alternately toward and away from a patient in the usual dental chair to thereby place the instrumentalities used by a dentist in carrying out dental operations within easy reach of the dentist, whether he is in a standing or seated position during the operation, and to permit the patient to readily seat himself in or remove himself from the dental chair, as desired.

This invention has for another important object the provision of a dental unit of improved construction and characterized by mounting a dental cabinet in pivotal relation to an upstanding tubular element or conduit through which one or more other conduits for energizing instrumentalities carried by the cabinet extend from a point below the surface of a floor or the like upwardly into the cabinet.

A further object of the invention is to provide a dental operating unit wherein the usual dental instruments, that are electrically energized or that utilize water, air, or other fluid material, are connected by conduits, or the like, which pass downwardly through the unit and emerge from the bottom of the unit, whence they are connected to suitable sources of supply, the point of egress of the conduits from the unit being out of sight.

A still further object of the invention is to provide a unit of the character indicated that is attractive, compact and sturdy in design; that is reasonable in initial and maintenance costs; and that is capable of performing its intended functions in an effective and trouble-free manner.

To the end that the above enumerated objects may be attained, I have developed a dental unit comprising a cabinet adapted to support or contain the various instruments and devices commonly employed in the practice of dentistry. These instruments and devices may include a warm air syringe, a warm water syringe, an electric drilling unit, one or more lights, a cauterizing instrumentality, a basin having water supply and drainage facilities, a gas burner and the

2

like. The foregoing instrumentalities and devices are suitably mounted to the cabinet and are connected by an improved conduit arrangement to appropriate sources of supply or energy located remotely from the cabinet.

10 The cabinet includes a pair of spaced-apart supports or pedestals that are joined together by a top. At least one of the pedestals is hollow, while either or both of the pedestals are mounted on roller means, such as swivel or fixed casters, as will be explained in detail further along.

One of the outstanding features of the invention is in the provision of an upstanding tubular member which is rigidly fastened to the floor and projects into the hollow pedestal through the bottom wall thereof. The tubular element serves two important functions. First, it constitutes a pivot about which the cabinet may be rotated so as to be moved toward or away from the usual dental chair at the will of the dentist; and second, it houses conduits whereby electricity, water, air or other gases are transmitted to the respective instruments carried by the cabinet top. These conduits enter the tubular element from beneath the surface of the floor, pass upwardly through the tubular element, and thence through the interior of the hollow pedestal and are connected to corresponding instrumentalities. In this manner, the conduits are completely out of sight and are so arranged as to obviate the possibility of a person stumbling or tripping over them, as may happen with conventional forms of construction wherein the conduits are exposed and present hazardous obstructions.

35 Access to the conduits in the course of assembly, for purposes of repair, or to place certain conduits into or out of active service, is attained through a hinged closure carried at the end of the hollow pedestal. Similarly, access to devices within the top is readily attained through 40 a hinged top cover.

The other pedestal is preferably provided with a series of drawers within which may be stored the usual accessory items of equipment used by 45 a dentist, such as drill bits, rotary brushes, scrapers, scalpels, forceps, and the like.

The roller means carried by the other pedestal preferably consists of a pair of spaced-apart casters that rotate about axes normal to the axis 50 of rotation of the cabinet with respect to the tubular element. By so arranging the casters, pivotal movement of the cabinet is facilitated and scuffing of or otherwise marring the floor is completely eliminated.

55 The above mentioned objects, as well as other

objects, together with the advantages obtainable by the employment of the apparatus of this invention, will be readily understood by persons versed in the art upon reference to the detailed description which follows, taken in conjunction with the annexed drawings, which respectively describe and illustrate preferred embodiments of the invention.

In the drawings:

Figure 1 is a perspective view of a dental unit constructed in accordance with the invention, with parts broken away and parts omitted for better illustration;

Figure 2 is a vertical cross-sectional view starting at a horizontal plane through line 2-2 of Figure 1;

Figure 3 is a bottom plan view of Figure 1 with parts omitted; and

Figure 4 is a view corresponding to Figure 2 and is illustrative of a modified form of the invention.

Referring now to the drawings, wherein like reference characters denote corresponding parts throughout the several views, and more particularly to Figure 1, a dental cabinet, generally indicated by numeral 10, includes a pair of spaced apart hollow supports or pedestals 11 and 12 having bottom walls 13 and 14, respectively. Bottom wall 13 of pedestal 11 is preferably made of metal and has a circular aperture 15 formed therein, as is best shown in Figure 2. A hollow top 16 is secured to the upper portion of and spans the space between the pedestals to thereby obtain a rigid unitary cabinet construction. Access to the interior of hollow pedestal 11 is gained through a vertically hinged door 17 in the outer side face of this pedestal. In a similar manner, access to the interior of hollow top 16 is attained by way of a top cover 18 that is coupled to the top by hinges 19. Pedestal 12 carries a series of sliding drawers, including drawers 20 and 21, for storing the usual accouterments employed by a dentist for purposes of examination, treatment and operation.

An upstanding tubular element 25, that is preferably a section of a right circular cylindrical conduit, has a ring 26 secured to its lower end by screws 27. The ring is provided with a plurality of lateral extensions 28 which receive screws 29 for fastening the ring to floor 30, whereby tubular element 25, by virtue of its connection with ring 26, is rigidly maintained in the illustrated upright position. As is shown in the drawings, tubular element 25 projects upwardly through aperture 15 and terminates within pedestal 11.

Secured to the under surface of pedestal 12 by a series of screws 31 is an arcuate bar 32. Roller means, such as a pair of spaced casters 33 and 34, are affixed to bar 32 and depend therefrom. Both of these casters are of the non-swivel type and are rotatable about corresponding axes, each of which is normal to the axis of tubular element 25. This relationship is indicated in Figure 3 where the axis of tubular element 25 is denoted by reference character 0, and where dash-dot lines AB and CD, that are coincident with the axes of casters 33 and 34, respectively, intersect at point 0. Also secured to and depending from pedestal 11 is a pair of spaced casters 35 that may be of the swivel or non-swivel type. It is recommended that casters 35 be of the non-swivel type and be rotatable about axes normal to the axis of tubular element 25, as in the case of casters 33 and 34 to avoid scuffing the floor surface.

Reference is next had to Figure 2 for details of construction of a pair of bearing means cooperating with hollow pedestal 11 and tubular element 25. One of these bearing means includes 5 a supporting ring or member 36 that is generally Z-shaped in cross section and that is attached to tubular element 25 by screws 37. Member 36 carries a bearing ring 38 having an annular raceway in its under surface for the reception of ball bearings 39. The other bearing means comprises a member 40, also generally Z-shaped in cross section, that is attached to bottom wall 13 of hollow pedestal 11 by screws 41. Within member 40 is a ring 42 having an annular raceway for ball bearings 43. It will be noted that the first and second described bearing means, respectively, prevent upward movement of pedestal 11 with respect to tubular element 25 and lateral movement of the pedestal with respect to the tubular element, while maintaining the tubular element out of engagement with the surface of bottom wall 13 that defines aperture 15.

Thus it will be observed that cabinet 10 is readily rotatable about the axis of tubular element 25 and may be, quickly and with a minimum of effort on the part of the dentist, moved toward or away from the usual dental chair. The arrangement above described minimizes friction between tubular element 25 and hollow pedestal 11. Additionally, this arrangement reduces frictional contact between the various casters and the surface of the floor, while effectively overcoming the possibility of these casters scuffing or otherwise marring the floor surface, particularly at such times as movement is initially imparted to the cabinet in either direction of rotation or when there is a change in direction of rotation of the cabinet.

Among the instruments normally employed 40 with my dental unit are a warm air syringe 44 and a warm water syringe 45 that are detachably secured to the cabinet by means of respective spring clips 46 and 47 mounted on the front face of hollow top 16. Also mounted on the front of the cabinet is a conventional dental cuspidor 48. Instrumentalities that extend upwardly of the top of the cabinet may include a Bunsen type gas burner 49 and an electrical drilling unit, generally indicated by numeral 50, which is connected to the upper end of a hollow post 51 by a universal coupling 52. The drilling unit depicted in Figure 1 includes an electric motor 53, a drive belt 54, and a drilling head 55.

Warm air, warm water, gas and electrical energy are transmitted to corresponding instruments and devices by suitable conduits, all of which enter into the interior of tubular element 25 from below the surface of floor 30, pass upwardly therethrough, and are connected to respective instruments and devices in a manner that will now be described. These conduits are best shown in Figure 1 and include a warm water conduit 60 having a shut-off valve 61 and communicating with a first branch conduit 62, that in turn connects with flexible tubing 63 which is coupled to warm water syringe 45, and a second branch conduit 65 that communicates with an outlet connection 66 for dental cuspidor 48. Excess water discharged by outlet connection 66 and mouth rinses and the like expectorated by a patient are received in dental cuspidor 48 and drained therefrom by way of a waste conduit 67, which in turn passes downwardly through the interior of hollow pedestal 11 and tubular element 25. A warm air conduit 70 communicates with a flexible tubing

64 that is connected to warm air syringe 44. A gas conduit 71 having a series shut-off valve 12 is in communication with gas burner 49. A conduit 75 contains a pair of electrical conductors 76 that are connected to a suitable transformer 77 which in turn is connected by conductors (not shown) within a conduit 78 to electrical terminal box 79. Electrical connection is established between terminal box 79 and electric motor 53 by way of electrical conductors (not shown) that extend through a conduit 80 and hollow post 51. A dial switch 81 carried by a panel board 82 within hollow top 16 is in electrical communication with terminal box 79 through the medium of conductors (not shown) in a conduit 83. As indicated in Figure 1, panel board 82 carries a plurality of switches for placing various devices (not shown) into and out of active service.

Each of conduits 60, 67, 70, 71 and 75 enters the interior of tubular element 25 from a point below the surface of the floor, extends upwardly therethrough and into hollow pedestal 11, and is then connected by corresponding other conduits to the various instrumentalities carried by the cabinet. A number of the conduits within the cabinet are either wholly flexible or have sections that are flexible to permit of rotation of the cabinet about tubular element 25 without damaging or breaking any of these conduits.

Reference is next had to Figure 4, which illustrates a modified form of the invention. In this embodiment, hollow pedestal 11 is not supported on casters, but instead is supported on a bearing means carried by tubular element 25. This bearing means consists of an annular support member 85 that embraces tubular element 25 and is attached thereto by screws 86, a bearing ring 87 within member 85, and carrying a series of ball bearings 88 in an annular raceway. A second bearing means maintains the surface of bottom wall 13 that defines aperture 15 out of engagement with the external surface of tubular element 25. This second bearing means includes a ring member 89 that is disposed within hollow pedestal 11 and is attached to the upper surface of bottom wall 13 by screws 90. Within member 89 is a bearing ring 91 having an annular raceway for guiding ball bearings 92. As in the case of the first embodiment of the invention illustrated in Figures 1 and 2, the members 85 and 89 of the second embodiment are generally Z-shaped in cross section.

From the foregoing, it is believed that the construction, operation, and advantages of my present invention will be readily comprehended by persons skilled in the art. It is to be clearly understood, however, that various changes in the apparatus set forth above may be made without departing from the scope of the invention, it being intended that all matter contained in the description or shown in the drawing shall be interpreted as illustrative only and not in a limiting sense.

I claim:

1. In apparatus of the character described adapted to be mounted on a floor or the like, a cabinet comprising a pair of spaced supports and a top secured to the upper portion of each support and spanning the space therebetween, one of said supports being hollow, an upstanding tubular member adapted to be rigidly attached to the floor and communicating with the interior of the hollow support through the lower end thereof, said cabinet being rotatable with respect to the tubular element, an instrument de-

tachably secured to the top, and a conduit connected to the instrument and extending through the interior of the hollow support and the tubular element.

5. In apparatus of the character described adapted to be mounted on a floor or the like, a cabinet comprising a pair of spaced supports and a top secured to the upper portion of each support and spanning the space therebetween, one of said supports being hollow, an upstanding tubular member adapted to be rigidly attached to the floor and communicating with the interior of the hollow support through the lower end thereof, said cabinet being rotatable with respect to the tubular element, instrumentalities utilizing electricity, water and gas carried by the top, and conduits connected to the instrumentalities and extending through the interior of the hollow support and the tubular element.

3. In apparatus of the character described adapted to be mounted on a floor or the like, a cabinet comprising a pair of spaced pedestals and a top secured to the upper portion of each pedestal and spanning the space therebetween, separate roller means attached to each of the pedestals and extending therebelow, one of said pedestals being hollow, an upstanding tubular member adapted to be rigidly attached to the floor and communicating with the interior of the hollow pedestal through the lower end thereof, said cabinet being rotatable with respect to the tubular element, an instrument detachably secured to the top, and a conduit connected to the instrument and extending through the interior of the hollow pedestal and tubular element.

4. In apparatus of the character described adapted to be mounted on a floor or the like, a cabinet comprising a pair of spaced pedestals and a top secured to the upper portion of each pedestal and spanning the space therebetween, one of said pedestals being hollow, roller means attached to the other of said pedestals only and extending therebelow, an upstanding tubular member adapted to be rigidly attached to the floor and communicating with the interior of the hollow pedestal through the lower end thereof, said cabinet being rotatable with respect to the tubular element, an instrument detachably secured to the top, and a conduit connected to the instrument and extending through the interior of the hollow pedestal and the tubular element.

5. In apparatus of the character described adapted to be mounted on a floor or the like, a cabinet comprising a pair of spaced pedestals and a top secured to the upper portion of each pedestal and spanning the space therebetween, one of said pedestals being hollow, roller means attached to the other of said pedestals and extending therebelow, an upstanding tubular member adapted to be rigidly attached to the floor and communicating with the interior of the hollow pedestal through the lower end thereof, said cabinet being rotatable with respect to the tubular element, said roller means being rotatable about an axis that is normal to the axis of rotation of the cabinet with respect to the tubular element, an instrument detachably secured to the top, and a conduit connected to the instrument and extending through the interior of the hollow pedestal and the tubular element.

6. In apparatus of the character described adapted to be mounted on a floor or the like, a cabinet comprising a pair of spaced pedestals and a top secured to the upper portion of each

pedestal and spanning the space therebetween, one of said pedestals being hollow, an upstanding tubular member adapted to be rigidly attached to the floor and communicating with the interior of the hollow pedestal through the lower end thereof, said cabinet being rotatable with respect to the tubular element, a pair of spaced rollers attached to the other of said pedestals and extending therebelow, each of said rollers being rotatable about respective axes that are normal to the axis of rotation of the cabinet with respect to the tubular element, instrumentalities utilizing electricity, water and gas carried by the top, and conduits connected to the instrumentalities and extending through the interior of the hollow pedestal and the tubular element.

7. In apparatus of the character described adapted to be mounted on a floor or the like, a cabinet comprising a pair of spaced pedestals and a top secured to the upper portion of each pedestal and spanning the space therebetween, one of said pedestals being hollow and including a bottom wall having an opening therethrough, an upstanding tubular member adapted to be rigidly attached to the floor and extending through the opening in the hollow pedestal, said cabinet being rotatable with respect to the tubular element, bearing means embracing the bottom wall of the hollow pedestal to prevent movement of the hollow pedestal in one direction along the axis of the tubular element and lateral movement of said cabinet with respect to the tubular element, an instrument detachably secured to the top, and a conduit connected to the instrument and extending through the interior of the hollow pedestal and the tubular element.

8. In apparatus of the character described adapted to be mounted on a floor or the like, a cabinet comprising a pair of spaced pedestals and a top secured to the upper portion of each pedestal and spanning the space therebetween, one of said pedestals being hollow and including a bottom wall having an opening therethrough, an upstanding tubular member adapted to be rigidly attached to the floor and extending through the opening in the hollow pedestal, said cabinet being rotatable with respect to the tubular element, a pair of spaced rollers attached to the other of said pedestals and extending therebelow, each of said rollers being rotatable about respective axes that are normal to the axis of rotation of the cabinet with respect to the tubular element, bearing means embracing the tubular element and engaging the bottom wall of the hollow pedestal to prevent movement of the hollow pedestal in one direction along the axis of the tubular element and lateral movement of said cabinet with respect to the tubular

element, an instrument detachably secured to the top, and a conduit connected to the instrument and extending through the interior of the hollow pedestal and the tubular element.

- 5 9. In apparatus of the character described adapted to be mounted on a floor or the like, a cabinet comprising a pair of spaced pedestals and a top secured to the upper portion of each pedestal and spanning the space therebetween, one of said pedestals being hollow and including a bottom wall having an opening therethrough, an upstanding tubular member adapted to be rigidly attached to the floor and extending through the opening in the hollow pedestal, said cabinet being rotatable with respect to the tubular element, means for supporting the hollow pedestal comprising a member embracing and affixed to the tubular element and bearing means carried by the member directly below the bottom wall of the hollow pedestal, an instrument detachably secured to the top, and a conduit connected to the instrument and extending through the interior of the hollow pedestal and the tubular element.
- 10 15 20 25 30 35 40 45 50 55 10. In apparatus of the character described adapted to be mounted on a floor or the like, a cabinet comprising a pair of spaced pedestals and a top secured to the upper portion of each pedestal and spanning the space therebetween, one of said pedestals being hollow and including a bottom wall having an opening therethrough, an upstanding tubular member adapted to be rigidly attached to the floor and extending through the opening in the hollow pedestal, said cabinet being rotatable with respect to the tubular element, a pair of spaced rollers attached to the other of said pedestals and extending therebelow, each of said rollers being rotatable about respective axes that are normal to the axis of rotation of the cabinet with respect to the tubular element, means for supporting the hollow pedestal comprising a member embracing and affixed to the tubular element and bearing means carried by the member directly below the bottom wall of the hollow pedestal, an instrument detachably secured to the top, and a conduit connected to the instrument and extending through the interior of the hollow pedestal and the tubular element.
